UNITED STATES PATENT OFFICE.

HANNAH LEWIS, OF NEW YORK, N. Y.

SMOCK.

Application filed April 13, 1926. Serial No. 101,879.

This invention relates generally to smocks, such as worn by women, the invention having more particular reference to a novel type of smock.

5 The invention has for an object the provision of an improved smock of novel construction and arrangement of parts.

For further comprehension of the invention, and of the objects and advantages 10 thereof, reference will be had to the following description and accompanying drawing, and to the appended claims in which the various novel features of the invention are more particularly set forth.

15 Fig. 1, of the drawing, illustrates my improved smock in use on a wearer.

Fig. 2, is a rear view thereof.

Fig. 3, is a fragmentary view illustrating a modification of my improved smock.

20 Fig. 4, is a fragmentary enlarged sectional view taken on the line 4—4 of Fig. 1.

Fig. 5, is a similar view, taken on the line 5—5 of Fig. 2.

Fig. 6, is a similar sectional view, to 25 that illustrated in Fig. 5, but showing a modification of the seaming and method of attaching the braiding thereto.

It will be understood that my improved smock may be made of any suitable materials, and in styles adapted for inside or 30 street wear, and to girls and women of all ages and figures, and particularly in such styles as may be in vogue for feminine wear. It will be further understood that my patent 35 refers more in particular to the construction thereof, arrangement of parts and manner of attaching the said parts.

As here embodied my improved smock consists of a garment of women's wear, embodying a yoke 10, of any suitable style, such as may be in vogue. It is to be understood that the yoke 10, is shaped and located in my improved smock, so as to replace the collar, which is generally used in garments 40 of this nature. The yoke 10 is stitched, or sewn to the sleeves 11, as at 12, the edges 45 13 and 14, or extremities of the yoke 10 and the sleeve 11 being turned in, and stitched, or sewn together, the braid 15, or 50 trimming being suitably stitched or sewn, on the exterior thereof, and directly over the said seam for covering the same and for providing a marginal outwardly projecting ridge adapted to simulate the free edge of 55 a folded lapel and collar. It is understood that the said sleeves 11, are of full length,

as clearly shown in Fig. 1 of the accompanying drawing.

Referring in particular to Fig. 5 of the accompanying drawing. It will be understood that the yoke 10 is sewn or stitched to the body 16 of my improved smock, as hereinbefore described, and clearly shown in the above referred to Fig. 5.

The yoke 10, is suitably finished, at its upper edge, by a tape 20, or any similar filler or padding, rolled so as to form an enlarged edge, the upper edge of the yoke 10 being turned in, so as to enclose or encase the tape 20, and suitably stitched as at 21 to cause 65 the free edges of said collar and lapel extensions to resemble folded edges of a folded collar and lapel.

Referring in particular to Fig. 3, of the accompanying drawing, in which I have 75 shown a modification of my improved smock, the sleeves 17 may be short, or semilength. The body 16, may be provided with shirring 18, or smocking, such as commonly used in feminine wearing apparel, suitably formed 80 in the said body 16, directly below the front of the yoke 10, and adjacent to the sleeves 17.

Referring in particular to Fig. 6 of the accompanying drawing in which I have illustrated a modification of the seaming and 85 method of attaching the braiding, the edges 13 and 14, or extremities of the yoke 10 and the sleeve 11, are turned in and stitched, or sewn together, the stitches being placed through the sleeve 11, adjacent to the edge 14 90 thereof, through the edge 14 and through the edge 13 of the yoke 10, so as to provide a more securely and positively sewn garment. It is to be understood that the above described method of sewing or stitching is not 95 necessarily limited to the yoke 10 and sleeve 11, but may be applied to all or any of the adjacent elements of my improved smock.

Having thus described my invention what I claim as new and desire to protect by Letters Patent of the United States is as follows:—

1. A smock of the class described comprising sleeve and body portions, a yoke having a back collar shaped portion, front lapel 105 shaped extensions on said yoke, the adjacent edges of said yoke, lapel extension, sleeve portions and body portions being disposed inwardly stitches securing said adjacent edges together, a braid secured to said adjacent edges and disposed over the joint therebetween for covering the same and for pro- 110

viding a marginal outwardly projecting ridge adapted to simulate the free edge of a folded lapel and collar, and a padding member disposed around the unattached edges of said collar and lapel portions, the material of said yoke being rolled around and secured to said padding to cause the free edges of said collar and lapel extensions to resemble folded edges of a folded collar and lapel.

2. In a smock of the class described comprising sleeve and body portions, a yoke having a collar shaped portion and lapel shaped extensions made integral therewith secured at its edges to said sleeve and body portions,

means disposed around the unattached edges of said yoke to cause said unattached edges to resemble folded edges of a folded lapel and collar, said yoke being located in said smock to replace the collar and lapels thereof, and a braid disposed over the joint between the yoke and the sleeve and body portions of said smock for covering the same, said braid being disposed outwardly from the surface of the material comprising said smock to simulate the free edges of a folded collar and lapel.

In testimony whereof I have affixed my signature.

HANNAH LEWIS.
